Patented Aug. 2, 1921.

UNITED STATES PATENT OFFICE.

JOSEPH GALLEAZZI, OF SAN FRANCISCO, CALIFORNIA.

EDUCATIONAL AND AMUSEMENT DEVICE.

1,386,248.

Specification of Letters Patent.

Patented Aug. 2, 1921.

Application filed October 25, 1920. Serial No. 419,299.

To all whom it may concern:

Be it known that I, JOSEPH GALLEAZZI, a citizen of the United States, residing at San Francisco, in the county of San Francisco and State of California, have invented new and useful Improvements in Educational and Amusement Devices, of which the following is a specification.

This invention relates to improvements in educational devices and resides in the provision of a novel, simply constructed and efficient device of this character which may be effectively used by school teachers, instructors and the like, particularly in the teaching of children, said device operating in such a way as to create interest and provide amusement whereby the instruction will be more impressive.

An object of the invention is to provide a device of the character described in which indicia such as the names of the Presidents of the United States, or State capitals, or numbers, dates or any other indicia will be presented in a unique manner so that they may be viewed and read, the operation of the device being such that upon each turning of a crank handle employed to operate the device, different indicia will appear and it will not be possible to determine in advance just what form of or just what particular indicia will be presented.

Another object of the invention is to provide means for regulating the display of indicia, so that, for instance, in the case of rows of numbers to be read and called out by the persons receiving the instruction or test, it is possible to display one or more of such numbers as desired.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Figure 1 is a front elevation of the edu-

cational and amusement device of my invention.

55

Fig. 2 is an end elevation of the device.

Fig. 3 is an end elevation, broken away and showing the arrangement of certain of the operating parts.

Fig. 4 is a rear elevation of the device with the rear wall or cover removed.

Fig. 5 is a sectional view taken on the line 5—5 of Fig. 1.

Fig. 6 is a fragmentary front elevation of a detail of the invention.

65

Referring to the present embodiment of the invention illustrated in the drawings, there is preferably provided a rectilinear casing 1 which houses the mechanism of the invention and is provided with a removable rear wall 2, whereby access to the mechanisms may be had.

Mounted within the casing 1 is a mechanism for presenting to view along an opening or slot 3 arranged horizontally in the front wall 4 of the casing, indicia of an interesting nature. This means comprises a horizontal rotary shaft 5 extending through the casing and suitably journaled in bearings 6 provided in opposite walls 7 of the casing. 75 The shaft projects out through both walls 7 and on one projecting end has a crank handle 8 suitably affixed thereto so as to provide for rotation of the shaft. On the other end of the shaft a pinion 9 is fixed and said pinion 85 meshes with a larger gear 10 rotatably mounted as at 11 upon one of the walls 7 of the casing. Loosely mounted upon the shaft 5 but so as to be rotated by the shaft when the latter is rotated are a plurality 90 of circular disks 12 which carry at suitably spaced points upon the peripheries thereof the indicia generally designated 13 and which are to be presented to view at the slot or opening 3. The disks 12 are mounted so 95 that they may revolve relatively but will rotate with the shaft due to the frictional engagement thereof with said shaft. There may be provided small washers 14 between the disks so as to prevent sticking of the 100 disks to one another. As shown in Figs. 1 and 2 the indicia are in the form of numbers on some of the disks so as to present a various combination of figures, for example,

in numbers of 10 figures. On other of the 105 disks the indicia represent the days, months,

and dates as well as the time both A. M. and P. M. whereby a combination of subject matter as shown in Fig. 1, reading "October 12, Friday, 10 A. M." and any or 5 all of the ten figures, may be presented. If desired, the names of Presidents of the United States or capitals of the various States or any other indicia which are instructive or interesting may be carried on the 10 peripheries of the disks.

I provide means for causing the relative rotation of the disks during the operation of the device so as to present different indicia at the opening or slot 3 for each operation of the device. In carrying this out, I provide on the peripheries of the disks a plurality of rows of stop members 15. These members 15 are adapted to engage a stop and releasing bar 16 which is pivoted at its 15 ends as at 17 to the wall 7 and extends across the row of disks on the rear side thereof. The bar 16 is adapted to be moved into and out of position to be engaged by said stop members 15. To provide for moving the bar 20 into and out of position, a cam member 18 is fixed upon the inner side of the gear 11. This cam member is adapted to engage a rocker arm 19 pivoted as at 20 to the adjacent wall 7. The arm 19 carries a pin 21 adapted to strike an extension 22 of the 25 bar 16 and cause the bar to be rocked on its pivots. A retractile spring 23 is secured as at 24 to the adjacent wall 7 and as at 25 to the bar 16 so as to normally hold said bar 30 in position to be engaged by said stops.

I provide means for regulating the amount of indicia that is to be displayed and said means is in the form of an arcuate shutter or plate 27 provided at its ends with right 40 angular extensions 28 pivotally mounted upon the shaft 5. This shutter regulates the size of the opening 3. One of the extensions 28 is provided with a sleeve 29 which surrounds the shaft and extends out through 45 one of the walls 7. As lever 30 is operated the plate 27 is moved so as to present a portion thereof between the opening 3 and those of the disks that are to be concealed. To facilitate the operation of this means, 50 a notched member 32 is fixed to one of the walls 7 so as to be concentric with the shaft 5 and said lever is arranged to operate over the notches 33 of said member 32 as shown at Fig. 2. Each notch will be numbered, 55 there being in this instance 10 of such notches. In moving the lever from the notch numbered 1, to the notch 5, as shown in Fig. 2, the plate 27 will be turned so as to conceal the first five numbers as shown in 60 Fig. 1, and permit only the last five numbers to be displayed. When the lever is at the first notch, only one number will be displayed, as all the rest will be concealed behind the plate. It will thus be seen that 65 with this means, it is possible to display

one or more as desired, of the different subject matters or indicia on the peripheries of the disks.

Operation.

Assuming the shutter 27 to be in the position as shown in Fig. 2 of the drawings, to operate the device, the handle 8 is turned several times so as to rotate the shaft 5. By reason of the fact that the stop members 70 15 engage upon the upper side of the bar 16 during the first few revolutions of the shaft, the disks are held against rotation. This is provided for by the large gear 11 which being considerably larger than the pinion 9 75 permits the shaft to be rotated several times before the cam 18 carried by said large gear moves into the position to engage and rock the arm 19. As soon as this cam engages 80 and rocks said arm 19 the pin 21 upon said arm will engage the extension 22 on the bar 16 and rock said bar so that it will move to the dotted line position shown in Fig. 5, out of the path of said stop members 15. As 85 soon as this takes place, the disks 15 rotate by frictional engagement thereof with the shaft 5. Since the disks depend upon this frictional engagement for their rotation, they will not be rotated correspondingly as some of the disks will have a tendency to 90 slip relative to the shaft while the others will be more directly rotated. This results in the relative rotation of the disks and causes the indicia to be changed as to being 95 presented at the opening 3. After the cam 100 18 has moved free of the arm 19, the spring 23 returns the bar 16 to normal position and as the stop members contact with said bar, the disks are brought into the position so 105 that the indicia thereon will aline and be presented at the opening 3. The disks are prevented from being further rotated as soon as the stop members 15 engage the bar 16. It will thus be seen that upon every 110 turning operation during which the cam 18 moves, the bar 16 out of position and the spring 23 returns said bar to normal position, the disks will be rotated differently and the indicia presented each time will be different. This element of uncertainty enhances the value of the device as it creates an 115 interest which is amusing and makes the instruction impressive. By the moving of the lever 30, the size of the opening 3 may be regulated by action of the shutter 27 so that 120 only part of the indicia will be presented while the other part is hidden. In the case of numbers, where the object is to have the pupils call off the numbers as they are presented at the opening 3, for primary instruction, only a few such numbers are presented, and when proficiency is reached in readily recognizing and calling off a few 125 numbers, the showing of numbers may be increased by adjustment of said shutter. 130

I claim:—

An educational and amusement device embodying in its construction a casing, one wall of which is provided with an opening, a shaft rotatably mounted within the casing, a plurality of disks mounted so as to rotate upon said shaft and provided with indicia on their peripheries arranged to be presented to view opposite said opening, a plu-

rality of stop members on said disks, stops 10 with which said stop members are adapted to engage to hold the disks against rotation upon the shaft, and means operated by rotation of the shaft for moving said stops out of stopping position whereby the disks are 15 free to rotate with the shaft.

JOSEPH GALLEAZZI.
